UNITED STATES PATENT OFFICE.

THOMAS JAMES BERRYMAN, OF ARMAGH, NORTHERN IRELAND.

SELECTING MECHANISM FOR TYPE-PRINTING TELEGRAPHY AND OTHER PURPOSES.

Application filed February 23, 1927, Serial No. 170,334, and in Great Britain February 26, 1926.

This invention relates to selecting mechanism more particularly for type-printing telegraph systems, although this invention like that constituting the subject matter of the 5 U. S. specification Serial No. 65,308, of Thomas James Berryman on which it is a modification or improvement is not limited to printing, as it may be used for effecting other operations under electric telegraph con- 10 trol.

The subject matter of the prior patent is a means for directly translating Morse code signals, the means consisting in the particular examples described therein, of two signal operated devices co-operating with a translating cylinder provided with grooves or projections so as to move the said cylinder axially and rotatively into different positions for different signals; the said translating cylinder either operating a type drum in the case 20 of printing or operating to close electrical circuits for giving any other required action.

Now this apparatus is also applicable to equal letter code signals provided that the 25 impulses of the different letters are received and treated in sequential order and other adjustments are effected as will be understood from the following description.

According to this invention the two signal 30 operated devices are arranged to respond in the sequential order of and to act differently for different impulses of the equal letter code and thereby causing the translating device to move differently for different letters of said code.

Other features of this invention will be apparent from the following description and will be more particularly pointed out in the 35 claims.

40 Referring to the drawings:-

Fig. 1 is an elevation illustrating diagrammatically one form of translating apparatus.

Fig. 1^a is an elevation of the escapement mechanism.

45 Fig. 2 is a plan view of the apparatus shown in Fig. 1.

Fig. 3 is an elevation of an alternative form of the apparatus shown in Fig. 1.

Fig. 4 is a plan view of the apparatus shown 50 in Fig. 3.

Fig. 5 is a fragmentary view of a modification of the apparatus shown in Fig. 3.

Fig. 6 is a further modification of the apparatus shown in Fig. 3.

Fig. 7 is a developed plan of a primary 55 form of translating cylinder for use with the form of apparatus shown in Figs. 1 and 2.

Fig. 8 is a similar view of a modified and simplified form of cylinder to that shown in Fig. 7. 60

Fig. 9 is a developed plan of the type drum corresponding to Fig. 8.

Figs. 10 and 11 are similar views to Figs. 7 and 8 but showing translating cylinders for the alternative form of apparatus shown in 65 Figs. 3 and 4.

Fig. 12 is a detail of the printing mechanism.

As the apparatus is not only applicable to printing it is proposed, in order to clarify 70 the description, to describe firstly the construction and operation of the apparatus for printing and then to indicate the construction and operation of the apparatus for other purposes. 75

In the first case consider the form of the apparatus shown in Figs. 1 and 2 of the accompanying drawings. In this case the means for translating the signals comprise an impelling device in the form of an escapement mechanism giving at each operation an increment of axial movement to the translating cylinder and control means cooperating with means on the translating device which will act when necessary to modify this movement of the translating device and in this way cause the device to act differently both for a difference in order as well as in the kind of impulses received. It will therefore be seen that the apparatus comprises four 80 main parts (1) the signal operated devices, (2) the translating device, (3) the printing mechanism, and (4) the restoring apparatus for returning the apparatus to its initial condition after the completion of each signal. 85 In order to facilitate description and reference, these parts will now be described separately.

Signal operated devices.

100

A polarized relay 1 (a relay in which the reed 2 is normally held in a central position and is moved to either side according to the character of the impulse) is provided, the magnets of which are energized by the signal current in the receiver circuit 3 and the relay acting when energized by impulses of either kind to close the local circuit 4 con-

nected with the magnet 5 operating the pins (of which only one, 6, is shown) of the escapement mechanism 7 for giving axial movement to the translating cylinder.

- 5 The local circuit 4 extends from the reed 2 around the magnet 5 around another magnet 12 (hereinafter described) to one contact 13 of the relay 1. The other contact 14 of the relay is connected by the conductor 15 to a contact 16 of a switch 17 in turn connected through a resistance 18 with the circuit 4. The circuit 4 contains a source of E. M. F. 19. The magnet 12 operates by means of the armature 20 the pins 32 and 33. An insulated 25 pin 24 is provided for operating the switch 17. This pin 24 is connected with the translating cylinder or a cam on a suitable shaft so that on receipt of the first positive impulse it is moved to close the switch.
- 20 Negative impulses act to move the reed 2 on to contact 14 which when the switch 17 is closed, closes the circuit through the conductor 15, switch 17, resistance 18, left hand part of circuit 4, magnet 5 and back through 25 the reed to contact 14. Positive impulses in the receiver circuit act to move the reed 2 on to contact 13 so as to close the whole circuit 4 through both magnets 12 and 5. The switch 17 is provided to prevent the magnet 5 being 30 energized by negative impulses at the commencement of each letter by preventing the local circuit from being closed until the reed has first been actuated by a positive impulse.

35 This is effected by normally retaining the switch open as shown by the member 24, the switch being reset at the end of each signal.

The magnet 12 is arranged to act faster than the magnet 5. In order to balance the local circuit and avoid excessive use of local 40 battery the resistance 18, equal to the resistance of the magnet 12 is provided, this resistance coming into use when the magnet 5 only is energized.

The magnet 5 attracts the armature 26 mounted upon the rocker 27 and moves this rocker against the action of the spring 28. This movement, through the medium of the stop 29 on the rocker 27 and the stop 31 on the arm 35, releases the pivoted arm 36 and 50 allows the pin 37 which contacts therewith to rise under the action of the spring 38 so that the pin 37 is moved out of engagement with the scape wheel 39 and allows this to rotate. At the same time the stop 40 on the member 27 engages with the stop 42 and moves the arm 43 downwardly, this arm depressing the pin 44 against the action of the spring 45 so that it moves into a position to engage with teeth on the scape wheel 46. These two scape wheels form a compound scape wheel which gives a similar effect to that of the well known fast and loose action of typewriter escapement mechanism whereby when the magnet 5 is energized the 65 scape wheel will take one step only. The

movement of the scape wheel is conveyed through the crank 49, the connecting rod 50 and universal joint 51 to the main shaft 52 and is arranged to give the shaft an increment of axial movement for each step of the escapement wheel, rotation of the universal joint being prevented by the pin 53 and stop 54.

The scape wheel 39 is provided with a stop 55 which on the resetting of the escapement as hereinafter explained rocks the arm 56 carrying the arm 35, which is pivoted at 59 and this ensures that the pin 44 is depressed.

Translating device.

Fig. 7 illustrates a primary form of translating device. In order that the construction and operation of this may be clearly understood this form will now be described and then the modification of the cylinder necessary to operate with the particular signal operated means described will be set out. When using a cylinder as shown in Fig. 7 the switch 17 will be dispensed with so that every impulse whether positive or negative acts on the magnet controlling the escapement for imparting axial movement to the translating cylinder. Another magnet is provided operated only on receipt of a positive impulse and acting on the pins which engage with the guides on the translating cylinder, which pins are marked 32 and 33 in Fig. 7 so that on receipt of a positive impulse, the pin 32 is withdrawn from the channel 60 with which it normally engages and the pin 33 will be inserted in the channel 61.

For each letter we shall have five impulses and as each impulse imparts a step of axial movement to the cylinder we shall have five steps of axial movement of the drum for each signal. These steps are indicated by the 105 transverse lines marked O, I, II, III, IV and V; O being the zero or starting point.

The operation will be readily understood from a description of the action on receipt of the signal representing B which consists of two negative impulses, followed by two positive impulses and a final negative impulse.

The first impulse being a negative impulse merely operates the magnet controlling the escapement and imparts one step of axial movement to the cylinder. As the magnet controlling the pins 32 and 33 is not energized the pin 32 will remain in engagement with the groove 60 and by reason of the axial movement imparted to the cylinder the latter 115 will be moved into a position in which the point 62 is beneath the pin 32.

As the channel 60 is inclined between the lines O and I, and as the pins 32 and 33 are stationary, the cylinder will be rotated. The next succeeding impulse being a negative impulse will act in a similar way and will bring the point 63 into a position beneath the pin 32 and impart further rotary movement to the cylinder. As the succeeding impulse is a 125

- positive impulse the cylinder will not only be given a step of axial movement but the pin 32 will be withdrawn from the groove 60 and the pin 33 will be inserted in the groove 64.
- 6 Now as the axial movement is imparted to the cylinder the point 65 will be brought into a position opposite the pin 33 and on the de-energization of the magnet controlling the pins 32 and 33 the pin 32 will be inserted in the channel 66 and the pin 33 withdrawn from the channel 64 leaving the point 67 beneath the pins 32. As however the next succeeding impulse is a positive impulse the magnet controlling the pins 32 and 33 will 15 again be operated withdrawing the pin 32 from the channel 66 and inserting the pin 33 in the channel 64 and the cylinder will be given a step of axial movement by this impulse, bringing the point 68 beneath the pin 33 and as before on deenergization of the magnet the pin 33 will be withdrawn and the pin 32 inserted in the channel 69 at the point marked 70. The final impulse being a negative impulse merely imparts a step of axial 20 movement to the drum bringing the point 71 opposite to the pin 32. This is the position of the cylinder corresponding to the letter B as indicated. In each case as the cylinder moves an equal amount for each letter the 25 printing action may be started by the translating cylinder and the apparatus may be restored to its initial condition (as hereinafter described).

In order to simplify the apparatus and to increase its speed it is preferred to employ the modified form of cylinder shown in Fig. 8 which is the form intended to be used with the apparatus shown in Fig. 1 of the accompanying drawings. The construction and 30 action of this form of cylinder will be clear from the following examples:—

Taking the letter B as before which is represented by two minus impulses followed by two positive impulses and a final negative impulse the two first impulses will have no effect upon the translating cylinder 79. The first positive impulse however will energize the magnet 12 causing it to withdraw the pin 32 from the channel 80 and insert the pin 33 35 in the channel 81 and as the magnet 5 controlling the escapement for giving axial movement will also be energized to act immediately after the magnet 12 the cylinder will be given one step of axial movement bringing the chain dotted line I into a position beneath the pin 33 and on the restoration of the means operating the pins 32 and 33 after the passage of this impulse the pin 33 will be withdrawn from the channel 81 and the pin 32 will be inserted in the channel 80. The next 40 succeeding impulse being a positive impulse, the pins and escapement mechanism will be actuated as before moving the point 82 on the chain dotted line II eventually into a position beneath the pin 32. The final impulse

being a negative impulse merely energizes the magnet 5 so as to impart a step of axial movement to the cylinder and the pin 32 being in the channel 83 which is inclined between the lines II and III will rotate the cylinder and 45 bring the point B thereon into a position beneath the pin 32.

If now this cylinder is coupled with the printing drum 84 shown in Fig. 9 in the manner shown in Figs. 1 and 2 the letter B will 50 be moved into printing position.

Printing.

The printing is effected by a type drum 84 fixed upon the shaft 52 so as to be moved by 55 the translating cylinder to bring the letters into a position for printing. The actual printing operation is effected by a printing hammer which moves the paper against the type at the end of each translating movement. 60 It is essential that the hammer should have a piano-like action in order to clear the drum after it has been operated. All this is well known in the art and need not therefore be 65 further described.

The type drum and (or) the type may be removable for replacement or alteration or for changing the position of the character in accordance with change of code.

Restoring apparatus.

It will be understood that at the end of each printing operation the apparatus must be restored to its initial or starting position. The apparatus for effecting this comprises the shaft 90 rockably mounted in the bearing 91, this shaft having an arm 92 which is operated, for instance, by the printing hammer at the end of the printing operation and rocks the shaft 90 which, in turn, operates the arm 93, which is so arranged as to retract both of the pins 32 and 33 from engagement with the channels in the cylinder and which shaft also actuates the arm 94, to reset the escapement mechanism in the well known manner. Thus 100 the escapement mechanism through the crank 49 and connecting rod 50 moves the main shaft 52 and therewith the cylinder axially into its initial position. In cases where the cylinder has been rotated, it is rotatively 105 moved into its initial position by the means, a suitable form of which is shown in the prior specification referred to.

It may be mentioned here that as a modification of the above described signal operated means two polarized magnets may be used, one operating each of the control pins 32 and 33 which engage with the grooves in the cylinder and it may be arranged that both of these magnets can, when excited, send a current through the magnet controlling the escapement mechanism for giving axial movement when the said polarized magnets are energized. In this case mechanical means for preventing the closing of the circuit of 110

the magnet controlling the escapement or to break this circuit will also be provided so that the escapement will not be actuated by negative impulses at the beginning of a letter as 5 aforesaid.

Having now considered the primary form of apparatus we will now consider applications of alternative form of the apparatus shown in Figs. 3 and 4 of the drawing for 10 the equal letter code system. Let us consider first of all the form of cylinder shown in Fig. 10. This cylinder is operated positively by an escapement mechanism adapted to give axial movement in the direction of the arrow 100 and the cylinder itself is arranged to act as an escapement to give rotary movement in the direction shown by the arrow 101 (in a manner which will be hereinafter described with reference to Figs. 3 and 4). In this case 15 mechanism for giving axial movement may be so arranged that it positively moves one step axially on the receipt of each negative impulse while the cylinder is allowed to rotate to an extent determined by the projections 20 102 thereon on the receipt of each positive impulse.

In this case a polarized relay may be provided so arranged that it is energized by the incoming impulses and serves to close a local 25 circuit either to the magnet controlling the axial escapement or the magnet controlling the pins 32 and 33, to give axial movement or allow rotary movement of the cylinder according to whether the impulse is a minus one 30 or a positive one as previously described. The operation in this case will be quite clear from the description of the operation on receipt of a signal representing the letter B, two minus impulses and two positive impulses and 35 a minus impulse in succession. The two minus impulses will merely act to cause the escapement to move the cylinder 103 in the direction of the arrow 100 bringing the point marked 105 into a position beneath the end 40 of the pin 32. The next impulse being a positive impulse will act to withdraw the pin 32 and insert the pin 33 which will allow the cylinder to rotate until the point 106 is in a position beneath the end of the pin 33. On 45 release of the magnet operating the pins 32 and 33 the pin 33 will be withdrawn and the pin 32 will be moved down on to the point marked 106. The next succeeding impulse being again a positive one will withdraw the pin 32 and move the pin 33 on to the point 50 marked 108 which will again allow the cylinder to rotate until the point 109 comes opposite the end of the pin 33 when again the restoration of the magnet operating the pins 32 and 33 will substitute the pin 32 for the pin 55 33. The final impulse being a negative one will merely move the cylinder axially to bring the space B into a position beneath the pin 32.

In the preferred form of this alternative 60 form of apparatus it is modified in a similar

way to the apparatus described with reference to Figs. 1 and 2 of the drawings so as to simplify the apparatus and increase the speed. This will now be described with reference to Fig. 11 which shows the translating 70 cylinder and Figs. 3 and 4 which show, by way of example, a practical embodiment of the apparatus.

The mechanical part of the apparatus shown in Figs. 3 and 4 in its essential features 75 differs only from that described with reference to Figs. 1 and 2 in the construction and operation of the translating device. In this case the escapement mechanism 110 is similar in all respects to that shown in Figs. 1 80 and 2 and it is operated by a magnet 125 to move the shaft 52 and with it the cylinder 112 in a direction opposite to that in Fig. 1 as indicated by the arrow. Also the cylinder acts as an escapement device being driven in 85 the example illustrated by the gear wheel 113 on the shaft meshing with the elongated pinion wheel 114 so arranged as to allow the gear wheel 113 to move axially without interfering with the driving connection. The pinion is driven by the gear wheel 116 from 90 a spring or other similar driving mechanism.

The cylinder in this construction is merely provided with a series of longitudinal ribs 95 118 serving virtually as guides on its periphery, these ribs being of different lengths as clearly shown in the developed plan, Fig. 11.

The polarized relay 120 is connected in the receiver circuit and serves to close either a local circuit consisting of conductors 121, 122, 123 and 124 containing the magnet 125 operating the escapement 110 which imparts axial movement to the shaft 52 or a local circuit consisting of conductors 127, 128 and 124 containing the magnet 129 which actuates the pins 32 and 33 according to whether the impulse is a minus one or a positive one respectively. The operation will be quite clear from what has been said with reference to Fig. 10 it only being necessary to add that a switch 130 similar in construction and operation to the switch 17, in Fig. 1 being connected in the circuit containing the magnet 125 which imparts axial movement to the translating cylinder so as to prevent the magnet 110 from being energized by the minus impulses at the commencement of a letter, the switch being released on receipt of the first positive impulse and thereafter the magnets and other parts will function as described with reference to Fig. 10.

In a modification of the alternative arrangement described with reference to Figs. 3 and 4, shown in Fig. 5, the polarized relay is dispensed with and the magnets 132 and 133 are polarized and are connected in series in the main line circuit 134, the magnet 132 being energized by positive impulses and the magnet 133 by negative impulses. The operation is the same as that of Figs. 3 and 4 130

except that instead of the switch breaking the circuit through the magnet 133, the switch 136 initially short circuits this through the circuit 137, 135 and earth 138, the switch being opened by the operation of the mechanism on receipt of first positive impulses.

In a further modification of the alternative arrangement shown in Fig. 6, again dispensing with the polarized relay, the two polarized magnets 140 and 141 are connected in parallel in the main line or receiver circuit 142 having an earth return 143. In this case the switch 144 acts to interrupt the circuit through the magnet 140 until the magnet 141 has been energized.

It will be understood in all cases where the five unit code is used and printing is to be effected a change-over arrangement from letters to figures or vice versa will have to be provided as the thirty one signals obtained are not sufficient for the letters, numerals, punctuation marks and other characters required, this may be effected in any convenient manner, for instance the change-over may be obtained by axial or rotary movement of the shaft relative to the translating cylinder or alternatively by slightly moving the printing hammer and tape to bring it opposite the different rows of type.

As shown in Fig. 12 the shaft carrying the printing drum is provided with a cam 150 which on rotary and (or) axial movement of the shaft allows the lever 151, pivoted at 149, to rock. This lever 151 carries a member 152 working in suitable guides. The member 152 is provided with projections 153—154 which serve to engage with and actuate a rocker 155 on which is mounted the platen 156 and tape guide 157, both the platen and tape guide being mounted on leaf springs 158 and 159 respectively. The retaining device 160 is provided to hold the rocker in either of its two positions determined by the stops 167 and 168. The striker 161 normally serving for knocking the platen and tape against the drum is actuated by the armature 168 of the printing magnet 162, but this is also used for actuating the rocker when letter blank or figure blank signals are received. It will be seen that on operation of the striker 161 by the armature 168 the member 152 will be lifted by the pin 163 and this will cause one of the projections 153—154 to engage with and move the rocker 155 according to the position of the lever 151 and thereby moves the platen and tape guide. The stop 169 limits movement of the member 152 and this engaging with the pin 163 prevents the striker moving sufficiently to knock the platen when letter blank or figure blank signals are received. When the type drum has passed both shift positions the lever 151 is held against the stop 164 by the weak spring 165 and the member 152 is then clear of the pin 163. A stop 166 is provided to prevent the

member 152 from falling beyond its normal position.

Where, instead of signals composed of impulses which are entirely separate, signals composed of impulses in which the consecutive impulses of the same kind run into one another (as, for instance, in the Murray automatic system) a vibrator or rotary or equivalent distributor or contact make and break device may be used to break the long signals into separate impulses or, as an alternative mechanism for producing timed sliding or rotary movement could be brought into action, to give the requisite movement of the translating cylinder.

In order to effect operation other than mere printing, the apparatus can be used for other purposes. The translating device may be used, for instance, to select a particular electrical contact and bring it into a position beneath a fixed contact so as to close a local circuit in a similar manner to the apparatus for this purpose described in my U. S. specification Serial No. 65,308.

I claim:

1. Selecting mechanism for type printing telegraphy and other purposes, comprising, a translating device adapted to partake of two movements, an impelling device for producing one movement, means on said translating device for determining the other movement, control means co-operating with said means on the translating device adapted quantitatively to vary the said other movement, and electro-magnetic means actuating said impelling device and said control means and arranged to act differently for different kinds of impulses received.

2. Selecting mechanism for type printing telegraphy and other purposes, comprising, a translating device adapted to partake of two movements, an impelling device for producing one movement, means on said translating device for determining the other movement, control means co-operating with said means on the translating device adapted quantitatively to vary the said other movement, electro-magnets controlling said impelling device and said control means and means for energizing said magnets differently by equal code impulses of different kinds.

3. Selecting mechanism for type printing telegraphy and other purposes, comprising, a translating device adapted to partake of two movements, an impelling device for producing one movement, means on said translating device for determining the other movement, control means co-operating with said means on the translating device adapted quantitatively to vary the said other movement, electro-magnets controlling said impelling device and said control means, a local circuit connected with said magnets and a main line relay in said local circuit adapted to energize the electro-magnets differently.

when actuated by equal letter code impulses of different kinds.

4. Selecting mechanism for type printing telegraphy and other purposes, comprising, a translating device adapted to partake of two movements, an impelling device for producing one movement, means on said translating device for determining the other movement, control means co-operating with said

10 means on the translating device adapted quantitatively to vary the said other movement, polarized electro-magnets, the magnet of one polarity being arranged to operate the said mechanical means on receipt of equal letter

15 code impulses of one kind and the magnet of the other polarity being arranged to operate the selective means on receipt of equal letter code impulses of the other kind.

5. Selecting mechanism for type printing

20 telegraphy and other purposes, comprising, a translating device adapted to partake of two movements, an impelling device for producing one movement, means on said translating device for determining the other movement,

25 control means co-operating with said means on the translating device adapted quantitatively to vary the said other movement, electro-magnetic means controlling said impelling device and said control means and ar-

30 ranged to be actuated differently by equal letter code impulses of different kinds and means for rendering one electro-magnetic means inoperative until the remaining electro-magnetic means has been operated.

35 6. Selecting mechanism for type printing telegraphy and other purposes, comprising, a translating device adapted to partake of two movements, an impelling device for producing one movement, means on said trans-

40 lating device for determining the other movement, control means co-operating with said means on the translating device adapted quantitatively to vary the said other move-

45 ment, electro-magnets controlling said impelling device and said control means, means for energizing said magnets differently by equal letter code impulses of different kinds and means for rendering one of said electro-

50 magnets inoperative by any impulse until the other electro-magnet has been operated.

7. Selecting mechanism for type printing telegraphy and other purposes, comprising, a translating device adapted to partake of two movements, an impelling device for pro-

55 ducing one movement, means on said translating device for determining the other movement, control means co-operating with said means on the translating device adapted quantitatively to vary the said other move-

60 ment, electro-magnets controlling said impelling device and said control means, a local circuit connected with said magnets a main line relay in said local circuit adapted to energize the electro-magnets differently when actuated

65 by equal letter code impulses of different

kinds and means for rendering one of said electro-magnets inoperative by any impulse until the other electro-magnet has been op- erated.

8. Selecting mechanism for type printing 70 telegraphy and other purposes, comprising, a translating device adapted to partake of two movements, an impelling device for pro-

75 ducing one movement, means on said trans- lating device for determining the other move- ment, control means co-operating with said

80 means on the translating device adapted quantitatively to vary the said other move- ment, polarized electro-magnets, the magnet of one polarity being arranged to actuate the said impelling device on receipt of equal letter code impulses of one kind, the magnet of the other polarity being arranged

85 to operate the control means on receipt of equal letter code impulses of the other kind and means for rendering one of said electro-

90 magnets inoperative by any impulse until the other electro-magnet has been operated.

9. Selecting mechanism for type printing telegraphy and other purposes, comprising, 90 a translating device adapted to partake of two movements, an impelling device for producing one movement, guides on said translating device, pins engaging said guides adapted to

95 select particular guides and to co-operate with the guides to produce the other move- ment, electro-magnets for operating said im- pelling device and for operating said pins and means for energizing said magnets different-

100 ly for equal letter code impulses of different kinds.

10. Selecting mechanism for type printing telegraphy and other purposes, comprising, a translating device adapted to partake of two movements, an impelling device for pro-

105 ducing one movement, guides on said trans- lating device, pins engaging said guides adapted to select particular guides and to co-operate with the guides to produce the other move- ment, electro-magnets for operat-

110 ing said impelling device and for operating said pins, means for energizing said magnets differently for equal letter code impulses of different kinds and means for rendering one of said electro-magnets inoperative by any

115 impulse until the other electro-magnet has been operated.

11. Selecting mechanism for type printing telegraphy and other purposes, comprising, a translating cylinder adapted to partake of both axial and rotary movements, an impell-

120 ing device for producing axial movement, guides on said cylinder for determining the rotary movement, pins engaging said guides adapted to select particular guides and co-

125 operating therewith to vary quantitatively the said rotary movement, electro-magnetic means controlling said impelling device and said pins, a local circuit connected to said electro-magnetic means and a polarized re-

130

lay adapted selectively to close the local circuit through the electro-magnetic means according to the kind of impulses received.

12. Selecting mechanism for type printing telegraphy and other purposes, comprising, a translating cylinder adapted to partake of both axial and rotary movements, an impelling device for producing axial movement, guides on said cylinder for determining the rotary movement, pins engaging said guides adapted to select particular guides and co-operating therewith to vary quantitatively said rotary movement, and two polarized electro-magnets, one operating the said impelling device on receipt of an equal letter code impulse of one kind and the other operating the said pins on receipt of an equal letter code impulse of the other kind.

13. Selecting mechanism for type printing telegraphy and other purposes, comprising, a translating device adapted to partake of two movements, an impelling device for producing one movement, means on said translating device for determining the other movement, control means co-operating with said means on the translating device adapted quantitatively to vary the said other movement, electro-magnetic means actuating said impelling device and said control means, a local circuit connected to said electro-magnetic means, a polarized relay adapted selectively to close the local circuit through the electro-magnetic means according to the kind of equal letter code impulses received and means for returning said translating device and said means to their initial position at the end of each signal.

14. Selecting mechanism for type printing telegraphy and other purposes, comprising, a translating device adapted to partake of two movements, an impelling device for producing one movement, means on said translating device for determining the other movement, control means co-operating with said means on the translating device adapted quantitatively to vary the said other movement, two polarized electro-magnets, one operating the said impelling device on receipt of an equal letter code impulse of one kind and the other operating the said control means on receipt of an equal letter code impulse of the other kind and means for returning said translating device and said means to their initial position at the end of each signal.

15. Selecting mechanism for type printing telegraphy and other purposes, comprising, a translating cylinder mounted for both axial and rotary movement; an escapement mechanism connected to said cylinder and adapted on operation to impart increments of axial movement to said cylinder, guides on the periphery of said cylinder, pins engaging said guides adapted to select particular guides and to co-operate with the guides to impart rotary motion to the said cylinder; electro-magnetic

magnetic means operating said escapement and selecting said pins; a local circuit connected to said electro-magnetic means; a polarized relay adapted selectively to close the local circuit through the electro-magnetic means according to the kind of impulses received and means for returning said translating device and said mechanism and said pins to their initial position at the end of each signal.

16. Selecting mechanism for type printing telegraphy and other purposes, comprising, a translating cylinder mounted for both axial and rotary movement; an escapement mechanism connected to said cylinder and adapted on operation to impart increments of axial movement to said cylinder; guides on the periphery of said cylinder; pins engaging said guides adapted to select particular guides and to co-operate with the guides to impart rotary motion to the said cylinder; two polarized electro-magnets, one operating the escapement and the other operating said pins, whereby the escapement is operated by equal letter code impulses of one kind and the pins are selected by impulses of the other kind and means for returning said translating device and said mechanism and said pins to their initial position at the end of each signal.

17. Selecting mechanism for type printing telegraphy and other purposes, comprising, a translating cylinder mounted for both axial and rotary movement; an escapement mechanism connected to said cylinder and adapted on operation to impart increments of axial movement to said cylinder; guides on the periphery of said cylinder pins engaging said guides adapted to select particular guides and to co-operate with the guides to impart rotary motion to the said cylinder; electro-magnetic means operating said escapement and selecting said pins; a local circuit connected to said electro-magnetic means and a polarized relay adapted selectively to close the local circuit through the electro-magnetic means according to the kind of impulses received.

18. Selecting mechanism for type printing telegraphy and other purposes, comprising, a translating cylinder mounted for both axial and rotary movement; an escapement mechanism connected to said cylinder and adapted on operation to impart increments of axial movement to said cylinder; guides on the periphery of said cylinder; pins engaging said guides adapted to select particular guides and to co-operate with the guides to impart rotary motion to the said cylinder and two polarized electro-magnets, one operating the escapement and the other operating said pins, whereby the escapement is operated by equal letter code impulses of one kind and the pins are selected by impulses of the other kind.

19. Selecting mechanism for type printing telegraphy and other purposes, comprising, a translating cylinder mounted for both axial and rotary movement; an escapement mech-

anism connected to said cylinder and adapted on operation to impart increments of axial movement to said cylinder; guides on the periphery of said cylinder; pins engaging said guides adapted to select particular guides and to co-operate with the guides to impart rotary motion to the said cylinder; electro-magnetic means operating said escapement and select-

ing said pins and means for causing the electro-magnetic means operating the escapement to act on receipt of every equal letter code impulse and for causing the electro-magnetic means controlling the pins to act on receipt of an equal letter code impulse of one kind only. 10

In testimony whereof I affix my signature.
THOMAS JAMES BERRYMAN.
